Primary Examiner—Susan J. Lucas

Assistant Examiner—M. H. Tung

Attorney, Agent, or Firm—Ralph D'Alessandro

CLAIM

The ornamental design for a urethane foam dispensing gun, as shown and described.

DESCRIPTION

FIG. 1 is a right side elevational view of a urethane foam dispensing gun showing our new design;

FIG. 2 is front elevational view thereof;

FIG. 3 is a left side elevational view thereof;

FIG. 4 is a rear elevational view thereof;

FIG. 5 is a bottom plan view thereof;

FIG. 6 is a top plan view thereof; and

FIG. 7 is a perspective view thereof.
